CARTON

Kenneth T. Butterly, Kalamazoo, Mich., assignor
to Sutherland Paper Company, Kalamazoo,
Mich.

Application June 1, 1942, Serial No. 445,288

3 Claims. (Cl. 229—31)

This invention relates to improvements in cartons.

The main objects of this invention are:

First, to provide a carton well adapted for the dispensing of foods which when set up quite effectively encloses or seals the same without the necessity of employing adhesives.

Second, to provide a carton having this advantage which may be readily set up and when set up is very strong and rigid.

Third, to provide a structure having these advantages which may be formed of an integral blank with little waste material.

Further objects pertaining to details and economies of the invention will definitely appear from the description to follow. The invention is defined in the claims.

A structure which embodies the features of the invention is clearly illustrated in the accompanying drawings in which:

Fig. 1 is a perspective view of a completely set up and closed carton embodying my invention.

Fig. 2 is an end elevation with one of the cover end flaps open showing the relation of the parts which it overlies and which are engaged thereby.

Fig. 3 is a perspective view of the body of the carton erected, the cover being open.

Fig. 4 is a fragmentary perspective view illustrating certain of the steps in erecting the carton.

Fig. 5 is a transverse section on a line corresponding to line 5—5 of Fig. 1 further illustrating the relation of parts.

Fig. 6 is a plan view of the blank from which the structure illustrated in Figs. 1—5 is formed.

Fig. 7 is a perspective view of a modified form or embodiment of my invention with the cover proper open.

The embodiment of my invention illustrated in Figs. 1—6, inclusive, comprises a bottom 1, front wall 2, rear wall 3, and end walls 4. These front, rear and end walls are hingedly connected to the bottom, the hinging means being indicated at 5 and 6 and being formed by scoring as is common practice in collapsible cartons.

The end walls and the front and rear walls are connected by corner members 7 which are hingedly connected to the end and front and rear walls by means of the scores 8. The corner members are diagonally scored at 9 to permit their being collapsed or folded when the walls are erected and also so that when collapsed they may be folded against the outer sides of the end walls. One pair of diagonally opposed corner members 7 have slots 10 extending from the outer edges thereof, that is, there are two slots 10 disposed

one on each triangular portion of the corner members so that when the corner members are collapsed the slots register as shown in Fig. 4. The other diagonally opposed pair has angular slits 11 therein which extend across the folding scores 9 so that when the corner members are collapsed downwardly opening slots or slits are provided for interlocking engagement with the slotted parts of the other diagonally opposed pair, 10 as is clearly shown in Fig. 3.

When thus engaged the box or carton is held in erected position and the end walls are held from collapsing inwardly. The cover 12 is hingedly connected to the upper edge of the rear wall by the score 13, the cover being provided at its front edge with a front closure member 14 which is hingedly connected to the cover 12 at 15. This closure member is provided with end closure flaps 16 conformed to provide tongues 17 which 20 project downwardly when the closure flaps 16 are lapped upon the erected corner members as shown in Fig. 2. The cover is also provided with end closure flaps 18 conformed to provide laterally projecting tongues 19 which may be tucked 25 or engaged beneath the lower edges of the corner members as shown in Fig. 1. When thus arranged the end flaps of the cover overlie or overlap the end closure flaps 16 of the front closure member 14 and one pair of the tongues of the end closures 30 18 engage the tongues 17 and then extend through the open-ended slots formed in the flaps 16 by the tongues 17, to beneath the corner members 7, so that the cover is not only securely retained in closed position, but an effective sealing of the 35 carton results.

The closed carton is very rigid and is capable of withstanding severe usage such as frequently results in merchandising goods where deliveries are made by persons who through haste or carelessness subject even fragile articles to rough handling. The cartons may be shipped or stored in the knockdown or flat as shown in Fig. 6 and are easily and quickly set up.

The body portion of the carton when set up remains in erected position, that is, the contents are not required to hold the walls in erected position as is the case with certain cartons now in use. After filling the carton may be quickly and securely closed. Although the cover and closure members are effectively retained, the carton may be easily opened.

In the modification or embodiment of my invention shown in Fig. 7 the front closure flap 20 is hingedly connected to the upper edge of the front wall at 21. This front closure flap is pro-

vided with end flaps 22 which overlie the erected corner members. The cover overlaps this closure flap and its end members, and they are securely retained by the end closure flaps 18 of the cover when such flaps are engaged or in fully erected position.

I have illustrated and described my invention in embodiments which I have found highly satisfactory. I have not attempted to illustrate or describe certain other embodiments or adaptations which I contemplate as it is believed the disclosure made will enable the embodiment of my invention as may be desired.

Having thus described my invention what I claim as new and desire to secure by Letters Patent is:

1. A carton comprising a bottom and front, rear and end walls hingedly connected to the bottom, corner members hingedly connected to the end walls and to the front and rear walls, said corner members being foldable diagonally and disposed against the outer sides of the end walls and having interlocking engagement with each other when in erected position, and a cover hingedly connected to the upper edge of the rear wall and provided with end closure flaps overlapping the ends and having tongues engageable beneath the lower edges of the interlocked corner members, said cover also having a front closure extension on its outer edge provided at its ends with end flaps disposed upon the outer sides of the erected corner members and having downwardly projecting tongues with which said tongues on the cover end closure flaps of said cover have interlocking retaining engagement when the last named tongues are engaged beneath the lower edges of said erected corner members.

2. A carton comprising a bottom and front, rear

and end walls hingedly connected to the bottom, corner members hingedly connected to the end walls and to the front and rear walls, said corner members being foldable diagonally and disposed against the outer sides of the end walls, means for holding said corner members in erected position, and a cover hingedly connected to the upper edge of the rear wall and provided with end closure flaps overlapping the ends and having tongues engageable beneath the lower edges of the corner members said cover having at its outer edge a front closure extension provided at its outer ends with end flaps having slots therethrough, through which certain of said tongues project when said tongues are engaged beneath the lower edges of the corner members whereby the front closure extension and also the cover are locked in closed position.

3. A carton comprising a bottom and front, rear and end walls hingedly connected to the bottom, corner members hingedly connected to the end walls and to the front and rear walls, said corner members being foldable diagonally and disposed against the outer sides of the end walls when erected, the pairs of corner members having means for holding the same when in erected position, and a cover hingedly connected to the upper edge of the rear wall and having a front closure member on its outer edge provided at its ends with flaps having downwardly projecting tongues and disposed upon the outer sides of the erected corner members, said cover also having end closure flaps engageable over said tongues and then beneath the lower edges of said erected corner members for locking the cover and also the front closure member in closed position.

KENNETH T. BUTTERY.
